GAME

Joseph A. Brocken, Warren, Ohio

Application March 10, 1939, Serial No. 261,065

1 Claim. (Cl. 273—108)

The present invention relates to games of a type intended to simulate the rolling of logs to a mill and embodies a game board having a surface provided with hazards over which a miniature log is intended to be rolled toward the central portion of the game board which represents the mill.

An object of the present invention is to provide a game device of this character which is amusing as well as involving a certain degree of skill in the manipulation of the log, which is relatively inexpensive to manufacture and otherwise well adapted for the purposes for which the same is intended.

15 Other objects and advantages reside in the details of construction as more fully hereinafter described and claimed, reference being had to the accompanying drawings forming part hereof, wherein like numerals refer to like parts throughout, and in which—

Figure 1 is a top plan view of the game board.

Figure 2 is a transverse sectional view taken substantially on a line 2—2 of Figure 1.

Figure 3 is a side elevational view of the imitation kant hook employed for moving the log, and

Figure 4 is a similar view of a miniature log designed for use upon the game board.

Referring now to the drawings in detail, the numeral 5 designates the game board which may be constructed of light-weight metal, cardboard or other suitable stiff material, and preferably of square shape in plan, the edges of the board being bent downwardly and inwardly to form a flange 6 providing a marginal support for the board, as clearly illustrated in Figure 2 of the drawings.

35 A groove or ditch 7 is formed in the upper surface of the board extending circumferentially around the marginal edges thereof, the outer walls of the ditch being slightly inclined as shown at 8, while the inner walls of the ditch are inclined abruptly as shown at 9, the upper edge of the walls 9 terminating in an upstanding bead

10 which extends continuously around the inner edge of the groove or ditch 7.

The surface of the board inwardly of the bead 10 is slightly inclined downwardly in an inward direction as shown at 11 terminating in an inner continuously extending ditch or groove 12, the latter being formed with spaced radially extending recesses 13 terminating at their inner ends in a raised flat surface 14.

10 The flat surface 14 is formed with an upstanding rib 15 of annular form forming the marginal edges of a pocket 16 in the surface of the game board and which bears a suitable legend, preferably the word "Mill."

15 In playing the game, a cylindrical game piece 17 is provided having rounded ends 18 and simulating a log. The game piece is placed in the outer ditch 7, and a manipulating tool 19 preferably representing a miniature kant hook is provided with tapered rounded end portions 20 20 which the player uses in an attempt to move the game piece out of the ditch 7, over the upstanding rib 10 and finally into the pocket 16.

It is believed the details of construction and manner of use of the various parts of the game 25 will be readily understood from the foregoing without further detailed explanation.

Having thus described the invention, what I claim is—

20 A game device comprising a game board having a continuous surface groove adjacent the marginal edges of the board the outer wall of the groove being gradually inclined, an upstanding rib forming the inner wall of the groove and rising above the surface of the board, a continuous 25 surface groove inwardly of the rib and separated from the rib by an inwardly inclined surface, radially extending recesses intersecting the last named groove and a pocket at the center of the board having walls rising from the surrounding 30 surface.

JOSEPH A. BROCKEN.
